 The Ohio Boxboard Company, Rittman, Ohio,
 a corporation of Ohio

Application December 11, 1951, Serial No. 260,994

5 Claims. (Cl. 229—28)

1

This invention relates to carrier cartons, and particularly to such cartons for packaging and transporting salable units of a predetermined number of bottles of beverages such as beer.

One object of the invention is to provide a carrier carton which may be shipped to the user in flat-folded condition, to thus economize in shipping space, and is capable of being erected to set-up, usable condition by automatic machines which may form a part of a production or packaging line installation such as would, for reasons of economy, be mandatory in a large bottling plant of the type employed for bottling at the source as is customary at breweries. A carton of the type provided by the invention therefore has advantages of facility and economy in handling for packaging over somewhat similar cartons which require manual setting-up operations.

A paperboard carton for bottled goods must have a strong bottom and a strong handle, and it must also provide a cellular structure by which the bottles are protected against breakage. In fact, shipping regulations covering the transportation by common carriers of bottles such as are used for beer require that the separators forming such cells must have a thickness of not less than 40 points (.040"). Carrier cartons produced in accordance with the present invention meet this requirement and also provide for the requisite strength of bottom and handle member while at the same time effecting an economy in material.

Moreover, due to certain structural refinements of the carton of the invention, its erection to set-up condition for use is greatly facilitated and its adaptability to automatic, machine erection for packaging line production is enhanced, all as will be explained hereinafter more fully and finally claimed.

In the accompanying drawings illustrating the invention, in the several figures of which like parts are similarly designated,

Fig. 1 is a plan view of the blank for forming the body and longitudinal partition member of the carton in accordance with the invention.

Fig. 2 is a plan view of the blank for the transverse partition member of the carton.

Fig. 3 is a plan view of the body blank of Fig. 1 folded and secured in flat-folded tubular condition,

Fig. 4 is a plan view of the carton body squared up from the condition shown in Fig. 3, and with its parts in position to be erected to set-up condition,

2

Fig. 5 is a perspective view of the transverse partition member (Fig. 2) in set-up condition,

Fig. 6 is a perspective view of the carton body as shown squared-up in Fig. 4, and showing the transverse partition member (Fig. 5) in one approved mode of association therewith to complete the assembly of the elements of the carton for erection to set-up, usable condition,

Fig. 7 is a view similar to Fig. 6, but showing another approved mode of association of the transverse partition member with the body,

Fig. 8 is an end view showing the associated parts of the carton in partially erected condition,

Fig. 9 is an end view showing the carton fully set up,

Fig. 10 is a side elevation of the carton in fully set-up condition,

Fig. 11 is a top plan view of the carton in fully set-up condition, and

Fig. 12 is a transverse sectional elevation of the set up carton taken on the line 12—12 of Fig. 10, the association of bottles therewith being shown in broken lines.

Having reference particularly to Fig. 1, it will be seen that the unitary body with longitudinal partition member of the carton of the invention is formed from an integral paperboard blank having appropriate cuts and folding scores defining a bottom wall 1 bounded at its side edges by the folding scores 2 and 3 and at its end edges by the folding scores 4 and 5. Offstanding from the side edges of the bottom wall 1 are side walls 6 and 7 defined by the longitudinal folding scores 2 and 3 and transverse folding scores 8, 8 and 9, 9 in substantially direct alignment with the end edge scores 4 and 5, respectively, of the bottom wall.

Joined to the side walls 6 and 7 on their end edges at the transverse folding scores 8, 8 are end wall members 10 and 11 each of substantially one-half the full width of the set-up carton end walls, and similar end wall members 12 and 13 are joined to the opposite end edges of the side walls 6 and 7, respectively, at their transverse folding scores 9, 9. Connected to the pairs of end wall members 10, 11 and 12, 13 on folding scores 14, 14 and 15, 15, respectively, are collapsible foldable web members 16, 17, respectively, which are also connected with the end edges of the bottom wall upon the folding scores 4 and 5, respectively, and these web members are furnished with diagonal, or gusset, folding scores 18 and 19, respectively.

Connected with the free edges of the end wall members 10 and 11 defined by the folding scores

20 and 21, respectively, are longitudinal partition members 22 and 23 adapted, when the carton is erected, to lie in face-to-face contact, and these partition members are provided, respectively, with pairs of mating, complementary slits 24 having special characteristics hereinafter pointed out. These partition members are also provided, respectively, with mating, complementary hand holes 25 furnished with conventional bendable flaps 26 which provide a suitable handle bearing or grip. One of the partition members, the member 23 as shown, carries at its outer (upper) edge a securing flap 27 bendable upon the folding score 28.

The end wall members 12 and 13 at the opposite edges of the side wall members 6 and 7 are provided at their free edges with attaching flaps 28 bendable upon folding scores 30.

The transverse partition member, Figs. 2 and 5, comprises a blank of paperboard material of a width substantially equal to the width of the bottom wall of the body and provided with transverse folding scores 31 spaced apart a distance substantially equal to the spacing of the slits 24 of the longitudinal partition members 22, 23, to provide U-legs 32 and a connection 33 between these legs. It will be noted, here, that the U-legs are of a height sufficient to completely separate the bodies of the packaged bottles (Fig. 12) up to their neck portions, and that the slits 24 in the longitudinal partition members extend outwardly (upwardly) from the inner edges of such partition members a distance at least equal to the height of such U-legs. Thus, in assembling and erecting the carton, effective cooperation and association of the two partition members can be obtained without any customary complementary partial slitting of the U-legs of the transverse partition member, whereby support is provided in accordance with the invention for the full height of the U-legs and automatic, mechanical assembly and erection of the carton is facilitated.

As delivered to the carton user or customer, for example a brewer or bottler, the body blank is folded upon the folding scores 30, 30 to bring the flaps 29 flat against the inner surfaces of the end wall members 12 and 13, and adhesive is preferably applied to the exposed surfaces of these flaps, and it is also folded upon the folding scores 3, 4, 8 so that the thus folded parts of the blank will be in juxtaposition and the free edges of the longitudinal partition members 22, 23 will overlap and be adhesively secured to the flaps 29 to assemble the carton body in flat, tubular form, as shown in Fig. 3. Of course, a plurality of the flat blanks for the transverse partition members, Fig. 2, will be furnished to conform to the number of carton bodies.

In the packaging line, whether the cartons are erected by mechanical means or manually, but preferably by mechanical means, the bodies are first squared up as shown in Figs. 4, 6 and 7, and the transverse partition members are bent upon their folding scores 31 to the form shown in Fig. 5, and then associated with the squared-up bodies in either of the modes shown in Figs. 6 and 7, respectively. Thereafter, as shown in Fig. 8, the side walls 6 and 7 are bent upwardly and inwardly toward each other until the longitudinal partition members 22 and 23 are brought into face-to-face contact, the webs 16 and 17 meantime folding inwardly upon their diagonal gusset folding scores 18 and 19, respectively, into flat-folded condition against the bottom wall 1 adjacent to its ends. At the same time, the trans-

verse partition member will be automatically positioned by the engagement of the body side walls 6 and 7 with the lateral edges of its U-legs 32 and the spanning of said legs by the slits 24 in the longitudinal partition members. It will be noted, moreover, that when the lateral partition member is pre-arranged as shown in Figs. 6 and 8, the erecting folding of the body will cause the connection 33 of the lateral partition member to strike against that portion of the opposite longitudinal partition member 22 which lies between the slits 24, but this portion will readily be distorted to permit the connection 33 to engage the bottom wall 1.

After the body and lateral partition member have been thus assembled and erected, the flap 27 on the longitudinal partition member 23 will be folded down against the outer face of the mating longitudinal partition member 22 (Figs. 10, 11 and 12) and these parts preferably rigidly connected as by adhesive or stitches or staples 34, Fig. 10. This arrangement of parts provides a triple thickness above the mating hand holes 25 and their flaps 26 and thus furnishes an exceptionally strong handle as is desired. Also, when the flaps 26 are bent through the hand holes in the conventional manner, as shown in Figs. 11 and 12, additional rigidity and strength are imparted to the handle.

As hereinbefore stated, regulations require that there be a thickness of at least 40 points (.040") of paperboard in the separators or partitions between bottles, and the carton of the invention satisfies this requirement while still providing an economy in paperboard stock. For example, the blank of the carton body may be made of paperboard stock of 20 point (.020") caliper, and the transverse partition member of 40 point (.040") caliper, thus not only furnishing separators or partitions of the required 40 point thickness but forming a heavy thickness for the carton bottom in areas where the bottoms of the bottles bear, it being obvious by reference to Fig. 11, that the bottles in the four end cells will rest upon the four thicknesses of paperboard provided by the carton bottom 1 and the triple thickness of the gusset folded web members 16 and 17, and the bottles in the two center cells will rest upon a double thickness of paperboard of at least 60 points caliper provided by the carton bottom 1 and the connection 33 of the transverse partition member.

It will be seen, therefore, that the invention provides not only for a carton which may be manufactured from relatively light caliper, and hence relatively inexpensive, paperboard, while still meeting all requirements of structural strength and rigidity and required bottle protection, but one which will lend itself readily to assembly and erection by automatic machinery.

Various changes and modifications are considered to be within the principle of the invention and the scope of the following claims.

What is claimed is:

1. A carrier carton, comprising a body formed from a paperboard blank provided with cuts and folding scores defining a bottom wall having side and end edges, a pair of similar side walls extending from opposite side edges of said bottom wall, each of said side walls having its end edges each provided with an end wall member of a width substantially equal to one-half the width of the end edges of the bottom wall, whereby when said end wall members are arranged in pairs such pairs will provide full-width end walls, the end

wall members of one pair being provided at their free edges with similar partition members, means for connecting the free edges of the end wall members of the other pair to the free edges of said partition members whereby said blank may be assembled into tubular form and may be erected by upward bending of said side wall members upon the folding scores defining the side edges of said bottom wall to bring said partition members into face-to-face relation and vertical to said bottom wall to provide a longitudinal partition, and a U-shaped transverse partition member supported by said bottom wall and having its U-legs upstanding transversely of said longitudinal partition, the partition members which together form such longitudinal partition being provided with mating slits extending from their lower edges upwardly a distance at least equal to the height of said U-legs to thus confine and support said U-legs throughout their height.

2. A carrier carton as claimed in claim 1, in which the end wall members are connected in pairs to the opposite end edges of the bottom wall by collapsible foldable web members serving to close the bottom of the carton at said end edges and to guide the longitudinal partition forming members during erection of the carton.

3. A carrier carton as claimed in claim 1, in which said longitudinal partition forming mem-

bers are provided with complementary mating openings to provide a handle.

4. A carrier carton as claimed in claim 1, in which one of said longitudinal partition forming members is provided with an attaching flap foldable into engagement with the other partition forming member for attachment thereto to maintain the carton in set-up condition.

5. A carrier carton as claimed in claim 1, in which the U-shaped partition member may be positioned within the tubularly formed carton body prior to erection of said body, and the slits of said longitudinal partition member will serve to clear the said U-legs when the carton body is bent to erected condition.
